UNITED STATES PATENT OFFICE.

DUNOIS E. SMITH, OF DENVER, COLORADO, ASSIGNOR TO THE COLORADO CRUDE OIL BURNER COMPANY, OF DENVER, COLORADO.

CRUDE-OIL BURNER.

SPECIFICATION forming part of Letters Patent No. 716,849, dated December 23, 1902.

Application filed May 9, 1902. Serial No. 106,824. (No model.)

To all whom it may concern:

Be it known that I, DUNOIS E. SMITH, a citizen of the United States of America, residing at Denver, in the county of Arapahoe and State of Colorado, have invented certain new and useful Improvements in Crude-Oil Burners; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in means for burning crude oil, my object being to provide a device of this class which shall be simple in construction, economical in cost, reliable, durable, and efficient in use; and to these ends the invention consists of the features, arrangements, and combinations hereinafter described and claimed, all of which will be fully understood by reference to the accompanying drawings, in which 25 is illustrated an embodiment thereof.

In the drawings, Figure 1 is a vertical longitudinal section of the device, taken on the line $x-x$, Fig. 2. Fig. 2 is a cross-section on the line $y-y$, Fig. 1.

30 The same reference characters indicate the same parts in all the views.

As shown in the drawings, my improved device consists of a number of trays 5, 6, and 7, arranged one above another, and an inclined plate 8, attached to the upper tray, to which the oil is fed in any suitable manner. As shown, the oil passes to the inclined plate from a pipe 9, having a valve 10 for controlling the flow. The plate is preferably curved 35 in cross-section, its concave surface being uppermost to receive the oil and carry its heavier or less volatile portion to the tray 5 below. The tray 5 is connected with the plate 8 by bolts 12 and 13, which pass through the connected parts and are surrounded by interposed sleeves 14 and 15, large enough to leave an air-space between the sleeves and the bolts, whereby the latter are protected from the heat. The sleeves also hold the plate 40 and upper tray apart. The tray 5 is provided with legs 5^a, which engage the tray 6, the

legs being of suitable length to hold the trays the proper distance apart. The tray 6 is also provided with legs 6^a, which engage the lowermost tray 7 for the same purpose. The trays 5 and 6 are provided with upraised parts 5^c and 6^c, respectively, and through these parts are formed openings 5^d and 6^d, respectively, through which the overflow passes from one tray to another. The raised parts 5^c and 6^c are only of sufficient height to maintain a shallow depth of liquid in the tray previous to the overflow from one tray to the other. The trays 5, 6, and 7 occupy a horizontal position and are provided with flanges 5^e, 6^e, 65 and 7^e, respectively, around their outer edges. These flanges prevent the overflow at the edges of the trays.

As soon as oil is discharged upon the plate 8 it is lighted and the most volatile portion 70 of the oil is burned on this plate, while the heavier or less volatile portion passes to the tray 5, where the part next in order of volatility is burned. A portion of the heavier oil will overflow from the tray 5 to the tray 6, 75 where another quality will be consumed, and if there is still any unconsumed oil it will pass to the bottom tray and be burned there. It will be understood that different degrees of heat are required to burn the different parts 80 of the oil. The part possessing the property of volatility in the highest degree will burn first, and so on, assuming that the burner is cold when the oil is lighted. As the oil flows down the inclined plate and overflows from 85 one tray to the other the heat of the burner is increasing, and by the time the heaviest portion of the oil has reached the bottom tray the heat of the burner will have attained a degree sufficient to consume this heaviest portion of the oil. 90

The burner when in use may be placed in the fire-box of an ordinary stove or range or in any other suitable receptacle. In the drawings a receptacle 12^b is shown provided with 95 air-holes 12^a at the bottom for draft purposes.

Having thus described my invention, what I claim is—

1. A crude-oil burner comprising a series of separated trays arranged one above the other and distinct the one from the other, an inclined plate mounted on the uppermost

tray and discharging thereon from the lower end of the plate, bolts connecting the inclined plate with the uppermost tray, sleeves surrounding the bolts and interposed between the tray and the plate, all the trays having flanges surrounding their outer edges, the trays between the inclined plate and the lowermost tray, having raised parts in their bottoms provided with openings for the overflow from one tray to the other, the raised parts being only of sufficient height to maintain a shallow body of liquid on the bottom, the trays between the inclined plate and the bottom tray, having supporting - legs whereby the trays are separated, substantially as described.

2. A crude-oil burner comprising a series

of trays, each tray except the lowermost having legs engaging the tray below, whereby the trays are suitably separated, the trays being 20 separate and distinct the one from the other, whereby the number used may be regulated at will, the trays being provided with flanges around their outer edges, and each tray except the lowermost having overflow-openings 25 surrounded by raised parts to maintain a shallow body of liquid on the bottom of the tray.

In testimony whereof I affix my signature in presence of two witnesses.

DUNOIS E. SMITH.
